ROTARY VALVE FOR INTERNAL
COMBUSTION ENGINESJean Vander Elst, Blanden-Louvain, and Joannes
Franciscus Backx, Louvain, BelgiumApplication December 23, 1932, Serial No. 648,666
In Belgium August 2, 1932

2 Claims. (Cl. 123—190)

The present invention relates to internal combustion engines of the type comprising a rotary valve distribution formed by means of a cylindrical body, in which channels are provided capable of putting the cylinder or cylinders of the engine successively in communication with the intake and the exhaust. This cylindrical rotary valve is generally mounted in a casing formed with two half-bearings in which the valve rotates, eventually with interposition of ball bearings; the lower half-bearing constitutes a cover for the cylinder end and has an intake port giving passage to the cylinder space; this half-bearing is relatively movable with respect to the cylinder, whereas the upper half-bearing is rigidly fixed to the cylinder wall, the mobility of the lower half-bearing securing a sufficiently supple and yielding position of the valve so as to avoid running hot or seizing of this valve.

According to the present invention and for the purpose of preventing to a maximum the transmission of the explosion and compression pressures of the cylinder upon the rotary valve, the half-bearing situated between the rotary valve and the cylinder end will be mounted upon a fixed element forming the cover of the cylinder end over a determined area, and in this auxiliary element is mounted a relatively movable plug or stopper of particular construction, the arrangement being such that said stopper will only receive a reduced portion of the explosion pressure of the cylinder and will only transmit said pressure to the rotary valve through a frictional contact of the smallest possible area existing between said stopper and the rotary valve.

The invention will be described hereafter with reference to the accompanying drawings.

Fig. 1 is a vertical axial section through an engine cylinder fitted with a rotary valve according to the invention;

Figs. 2 and 3 illustrate an axial section and a plan view of the particular stopper used in the latter form of embodiment.

Fig. 4 is a vertical section through a part of the motor, along a plane containing the rotary valve axis.

With reference to Fig. 1, the rotary valve 1 is formed by means of a hollow cylindrical body, in which are provided four curved channels 2, which open into the periphery of the cylindrical body at A and B. The lower half-bearing 3 for the valve is placed upon the end of the cylinder 5 with interposition of at least four helical springs 25 fixed and lodged upon an intermediary element 3' rigidly fixed at the end of the cylinder.

der 5 and forming a partial cover thereon; this intermediary element 3' may also be cast with the cylinder body and comprises a jacket for the circulation of cooling water. This half-bearing 3 thus freely movable and slightly pressed by the springs 25 constitutes a cradle for the rotary valve 1, the upper half of which is covered by the upper half-bearing 4. This latter is rigidly fixed to the cylinder wall 5 by means of bolts 17.

The valve 1 is mounted at its ends in roller or ball bearings 19, Fig. 4 and preferably the upper half-bearing is not in contact with the valve 1. As a result, at each explosion, the bearings 19 will have to resist a stress tending to lift the rotary valve and must be constructed accordingly. The cylinder 5 communicates with the rotary valve through a channel C' provided in the floating stopper element 26 described hereafter.

As illustrated, the upper half-bearing 4 completely and tightly encloses the lower-half-bearing 3; 7 and 8 designate respectively the intake and exhaust ports provided in the upper cover 4, and 9 and 10 designate respectively the intake and exhaust ports provided in the lower half-bearing 3. The latter has also a circulation of cooling water which communicates with that of the cover 3' with interposition of rubber rings 11.

The four channels 2 successively work for intake and exhaust. Said channels 2 have their walls not strictly parallel to each other; they are of a larger section at A than at B, so as to differentiate the period of exhaust from that of intake.

The cooling water accumulating heat tends to equalize the temperature of the passages 9 and 10 and it results therefrom that the intake is heated and that the exhaust is cooled by said circulating water.

The rotary motion of the valve is secured by the crank-shaft and by means of a convenient transmission either by endless chains or toothed gears.

In the central portion of the half-bearing 3 and of the intermediary element 3' is mounted a particular stopper 26, constructed in the shape of a piston having two diameters. This stopper is cylindrically bored and this bore ends in a cone towards the upper end and forms in a projecting portion 32 a slot C' opening upon the rotary valve. Rings 30 and 31 secure tightness with the bores made in the elements 3 and 3' and a helical spring 29 slightly presses the stopper 26 against the valve 1.

The fuel mixture is sucked through the channels 9 and 2, and conducted towards the cylinder

5 through the slot C' and the bore of the stopper 26.

The stopper 26 closes the cylinder chamber although securing a friction and pressure surface as small as possible against the rotary valve 1.

Lubrication is secured by an oil compartment 36 having an overflow and fed by the usual oil pump of the engine. The oil container is provided with a wick contacting with the roller 27, which is rotated by the rotary valve, so that a regular and complete lubrication is performed.

The cooling channel 28 also communicates with the water circulation of the valve and the cooling pump (not shown) of the engine.

At the moment of explosion, the stopper 26 undergoes a supplementary thrust which is transmitted to the rotary valve through the friction surface 26' surrounding the slot C', which, for the purpose, is of the smallest possible area. A smaller excess of pressure is exerted upon the stopper 26 during the compression stroke, and such excess of pressure prevents the escape of the compressed fuel mixture between the contacting surfaces 26'.

In this embodiment, the half-bearing 3 only affords passage for intake and exhaust and for securing lubrication, and this half-bearing has no other pressure effect than that from springs 25.

It must be said that the stopper 26 does not necessarily require the shape of a cylindrical piston, but this shape is preferable, as tightness may be more easily secured by means of piston rings.

This construction provides for a reduced friction and a more intensive lubrication between the rotary valve and its casing.

This construction allows an easy dismantling of the engine, so that the stopper 26 may be instantaneously replaced.

The rotary distribution according to the present invention secures an advantageous and simple construction, as many mechanical elements are eliminated, such as cam shafts, automatic valves, multiple slide valves and the like.

Wear upon the elements is automatically com-

pensated and the pressure and friction upon the rotary valve remain nearly constant, and cooling is easily controlled and adjusted. By removing the cover 18, it is possible to observe the working of the lubrication. As the valve rotates slowly owing to the plurality of inner channels, and by the fact that the construction remains essentially symmetrical and of rigid mechanical calculation, the engine works noiselessly.

We claim:

1. A rotary valve for an internal combustion engine, comprising a tubular rotary member having inner transversely arranged channels, turning in a ported casing constituted by means of two half-bearings, one half-bearing being free and yielding between the tubular valve member and a cover closing the cylinder end, said half-bearing and cover having corresponding passages opening in the cylinder, bearings supporting the rotary valve member at each end, a stopper tightly fitting in said passages and yielding against the rotary valve member and having a bore and slot for securing communication between the rotary valve member and the cylinder, the other half-bearing tightly enclosing the aforesaid one being bolted to the cylinder end, substantially as set forth.

2. A rotary valve for internal combustion engine, comprising a tubular rotary member having inner transversely arranged channels, turning in a ported casing constituted by means of two half-bearings, one half-bearing being free and yielding between the tubular valve member and a cover closing the cylinder end, said half-bearing and cover having central coaxial bores, bearings supporting the rotary valve member at each end, a hollow cylindrical stopper fitting in said bores, a helical spring pressing the stopper against the rotary valve member, said stopper having a slotted projection fitting in a seat cut in the curved portion of the half-bearing, the other half-bearing tightly enclosing the aforesaid one being bolted to the cylinder end, substantially as set forth.

JEAN VANDER ELST.
JOANNES FRANCISCUS BACKX.
